CANADA.

LOG RAFT.

Application filed March 20, 1923. Serial No. 626,355.

To all whom it may concern:

Be it known that we, GILBERT G. DAVIS and MATTHEW J. DAVIS, both residents of the city of Vancouver, in the Province of 5 British Columbia, Canada, have invented certain new and useful Improvements in Log Rafts, of which the following is a specification.

Our invention relates to improvements in 10 log rafts, the objects of which are to provide means whereby the logs forming the raft are bound together that the raft may be towed through heavy seas without damage or loss of logs therefrom, a further object being to provide a means whereby the 15 raft becomes more tightly bound during the process of towing it through the seas than is possible when constructing the raft either on a launching cradle or in the water, and 20 also to provide a fastening for the chain bindings which will admit of the raft being readily broken up when desired.

Our invention consists essentially of a 25 raft floor having side booms and upon which floor tiers of logs are placed and bound, and a pair of centre sticks spaced apart to which binding ropes are attached for encompassing the superimposed tiers, and means for imparting endwise movement of the centre 30 sticks one towards the other as the raft is being towed, to effect a tightening of the binding ropes attached thereto, as will be more fully described in the following specification, in which:—

35 Fig. 1 is a cross sectional view taken on the line 1—1 of Fig. 3.

Fig. 2 is a cross sectional view taken on the line 2—2 of Fig. 3.

40 Fig. 3 is a sectional plan view showing the arrangement of the centre sticks and the towing lines.

Fig. 4 is a view of the chain binding clip.

In the drawings like characters of reference indicate corresponding parts in each 45 figure.

With a view to more clearly showing the manner in which the raft is constructed and bound together, the logs and bindings are widely spaced in the drawing, one complete 50 series of bindings being shown in a single

transverse plane, though in practice these are distributed throughout the length of the raft.

The numeral 1, (see Fig. 1) indicates a tier of logs forming a floor to the raft. 2 55 indicates a pair of side booms which may be formed of a row of single logs in alignment with each other and bound together end to end, or formed of sets of three logs as shown, such sets of logs being in alignment throughout the length of the boom, the 60 end joints being broken or lapped as shown in Fig. 3. 3 indicates a pair of cables one passing over one side boom 2, under the floor tier 1 and over the opposite side boom, the 65 other passing under the side booms 2 and over the floor tier 1, the ends of the cables 3 being drawn tightly together and suitably fastened. 4, 5, 6, 7 and 8 indicate tiers of logs laid successively above the tier 1 to 70 form the raft, and 4^a, 6^a, and 7^a are the side logs of each of the respective tiers.

The numeral 9 is a cable overlying the 75 floor tier 1 having its extremities brought up through the tier 4 on the inner side of the logs 4^a, the cable ends are then laid out on opposite sides of the raft pending the building up of the further tiers. 10 indicates a pair of centre sticks disposed longitudinally of the raft and spaced an appreciable distance apart (see Fig. 3), these sticks will preferably be laid with their smaller ends directed to the longitudinal centre of the raft, at the inner end of each of the centre sticks 10 is attached a block 80 11 (see Fig. 3) the purpose of which will hereinafter appear.

The numeral 12 indicates a further block 85 attached to the outer end of one of the centre sticks 10 adjacent the forward end of the raft. 13 indicates a pair of cables one end of each being secured to a shackle 14, the opposite ends being each secured to the forward end of a side boom 2. 15 is a tow line by which the raft is attached to a tug, and 90 upon the outer end of which a block 16 is attached. 17 is a further cable having one end secured to the shackle 14 from whence it is passed through the blocks 16, 12 and 11 95 respectively, to obtain the desired purchase, 100

while its opposite end is secured adjacent the block 11 of the after centre stick 10.

A plurality of cables indicated by the numeral 18 are looped at their inner ends about 5 the centre sticks, their free ends passing under tier 5 up on the inner side of the side logs 5^a and laid out pending the laying of the further tiers. We may prefer to pass 10 each of the cables 18 outwardly of the raft under a side boom 2 and from thence over 15 the raft to be ultimately attached to the opposite side boom 2. 19 and 20 are further cables laid between the tiers 5 and 6, and 6 and 7, which are laid out in a manner similar 20 to those before mentioned. Simultaneously with the building up of the several tiers of logs and the laying of the cables therebetween we lay a plurality of chains 21, 21^a and 21^b, one above the other under the 25 floor tier 1 and between different tiers of logs adjacent the forward and after ends of the raft, as shown in Fig. 2, the ends of each tier being fastened outside the raft to the chain above it by clips 23, the topmost chain 21^b having its ends brought up over the top 30 tier of logs and fastened together with a clip 23. 22 are further chains having an eye at one end which is connected to the lowermost chain 21 and is passed tightly 35 around a side boom 2 and is clipped at its upper end to the chain 21^a. When the several tiers of logs are laid up the free ends of the cables 9, 18, 19 and 20 are passed over the top of the raft in opposite directions and 40 are passed around the side booms 2 and suitably clipped upon themselves.

The numeral 23 indicates, in general, a 45 clip shown in detail in Fig. 4, by which the chains are fastened to each other which consists of a pair of shackles 24 and 26 formed by bending a piece of metal back upon itself, the shackle 24 having straight legs 25, and the shackle 26 having offset legs 27 adapted to fit outside the legs 25, the legs of the 50 shackles 24 and 26 are spaced apart a distance slightly greater than the material used in forming the chain links to be clipped. 28 are slots through both legs of each shackle in which a bolt 29 is inserted to 55 fasten the shackles together. 30 is a cotter pin for the purpose of preventing the bolt 29 from being inadvertently withdrawn from the slots 28.

Having thus described the several parts 55 of our invention, we will now briefly explain the manner in which it functions.

The raft having been constructed in the manner before described the tow line 15 is made fast to a tug and the raft started 60 towards its destination. The constant pulling strain of the tug on the tow line 15 is transmitted to the side booms 2 through the line 13 and also to the inner ends of the centre sticks 10 through the line 17 tend-

ing to draw the sticks 10 endwise towards 65 each other, any such movement of the centre sticks will simultaneously draw the looped ends of the ropes 18 towards the longitudinal centre of the raft thereby effecting an increasing binding strain upon all the 70 logs that they each encompass. The centre sticks being tapered will on being drawn inwardly by the towing action impose a wedging strain upon the logs forming the raft, thus further tightening the several 75 bindings around the raft.

When the raft is to be broken up it suffices to withdraw the bolts 29 from the clips 23 and disconnect the several cables, when the raft will spread apart allowing 80 the logs to come to rest in the water.

What we claim as our invention is:

1. In a log raft, a raft floor having side booms to which the floor is connected, logs arranged in tiers upon the floor, binding 85 ropes underlying the tiers the ends of which pass over the top of the raft and are secured to the side booms.

2. In a log raft, a raft floor having side booms to which the floor is connected, logs 90 arranged in tiers upon the floor, binding chains underlying the tiers the ends of one chain being connected to the next chain above and the ends of the topmost chain being connected together on the top of the 95 raft.

3. In a log raft, a raft floor having side booms to which the floor is connected, logs arranged in tiers upon the floor, binding 100 chains underlying the tiers, each chain being connected adjacent the ends to the next chain above, the ends of the topmost chain being connected together on the top of the raft and chain connections between the raft and the side booms.

4. In a log raft a plurality of tiers of logs laid up one above the other, side booms to the raft, a longitudinally disposed centre stick having binding ropes extending at right angles outwards of the raft, the free 110 ends of the ropes being passed circumferentially of the raft and fastened to the side booms, and means for drawing the centre stick endwise of the raft as the raft is towed.

5. In a log raft, a plurality of tiers of logs 115 laid up one above the other and bound together, a pair of axially aligned longitudinal centre sticks, said centre sticks being tapered and disposed with their thin ends towards the longitudinal centre of the raft, 120 and means connecting the centre sticks whereby they are drawn inwardly of the raft to wedge the logs against the bindings.

6. In a log raft, a plurality of tiers of logs 125 laid up one above the other, side booms to the raft, a pair of axially aligned centre sticks spaced part having binding ropes extending at right angles outwards of the raft,

the free ends of the ropes being passed circumferentially of the raft and fastened to the side booms, and means for drawing the centre sticks towards each other as the

5 raft is towed.

7. In a log raft, a plurality of tiers of logs laid up one above the other, side booms to the raft, bindings for the raft connected at one end to the centre stick, towing lines

10 connecting the side booms and the centre sticks whereby a tightening strain is im-

posed upon the raft bindings as the raft is being towed.

Dated at Newport, Ore., this 17th day of February 1923.
